WELL DRILLING APPARATUS

Spencer W. Long, Inglewood, Calif., assignor to
 Baash-Ross Tool Company, Los Angeles, Calif.,
 a corporation of California

Application March 27, 1940, Serial No. 326,216

15 Claims. (Cl. 255—23)

This invention relates to well drilling equipment and relates more particularly to rotary table bushings for use in the rotary method of well drilling. A general object of this invention is to provide a practical, effective and easily handled arrangement or combination of bushing elements for use in the rotary table of a well drilling rig.

The master bushings of rotary tables have for many years been formed with a central opening having a flat walled polygonal upper portion for receiving the drive bushing or Kelly bushing, to provide a torque drive to the Kelly bushing, and a lower portion that is conical or tapered to receive the slips. With the present day drilling practice it is desirable to employ long slips and to provide increased bearing surfaces in the master bushing for receiving the lengthened slips. Master bushing and Kelly bushing assemblies have recently been introduced in which the central opening of the master bushing is tapered to the top of the master bushing to provide ample bearing surfaces for the long slips and the Kelly bushing is formed to seat on the top of the master bushing. In this last named construction the Kelly bushing has pins projecting from its lower side and received in spaced openings in the top of the master bushing to transmit rotation or torque from the master bushing to the Kelly bushing. The new type of bushing construction is successful and effective but has certain disadvantages. Considerable difficulty is often encountered in centering or orienting the new type of Kelly bushing to bring its torque transmitting pins into alignment with the openings in the master bushing. If the Kelly hangs out of alignment when being lowered into position it is often necessary to resort to sledging, barring, or other time consuming operations to bring the Kelly bushing into position to enter its pins into the openings of the master bushing. Further, the new pin type Kelly bushing is usually held down against vertical shifting by manually operated latches. The manual conditioning and releasing of these latches requires considerable time and there is always the danger of damaging the equipment by raising the Kelly bushing before the hold down latches are released.

Another object of this invention is to provide a master bushing and Kelly bushing construction of the "pin" torque transmission type wherein the tapered slip receiving opening of the master bushing may be increased to maximum length and characterized by novel means for automatically centering the Kelly bushing as the same is lowered into the master bushing, so that the torque transmitting parts are immediately oriented and

readily entered in the openings of the master bushing by merely starting rotation of the rotary table.

Another object of this invention is to provide a bushing construction of the character mentioned in which the Kelly bushing is immediately and automatically secured or latched against vertical movement relative to the master bushing when brought to the operative position and is automatically freed for upward movement upon being hoisted from the master bushing. The construction of the present invention embodies a novel means for holding the Kelly bushing against upward movement that is set or conditioned without manual operation when the Kelly bushing assumes its operative position and that is released without manual attention when the Kelly bushing is hoisted from the master bushing.

Another object of this invention is to provide a bushing construction of the character referred to embodying improved means for transmitting torque between the master bushing and the Kelly bushing. The improved torque transmitting means of the invention embodies radially disposed cooperating surfaces on the master and Kelly bushings presenting much larger effective areas than the torque transmitting means heretofore used.

Another object of this invention is to provide a Kelly bushing having a guide part or pilot part on its lower end adapted to enter the central opening of the master bushing to automatically center the Kelly bushing as it is lowered into place.

Another object of this invention is to provide a Kelly bushing and master bushing combination of the character mentioned in which automatic latch means are associated with the pilot part of the Kelly bushing to automatically latch the Kelly bushing against vertical displacement when it is lowered into place in the master bushing.

Another object of this invention is to provide a bushing construction of the character mentioned embodying a roller Kelly bushing including rotatable elements for cooperating with the drive stem or Kelly to reduce friction to a minimum.

A further object of this invention is to provide a bushing construction of the character mentioned that is sturdy, long-wearing, and particularly easy to manipulate and control.

The various objects and features of my invention will be fully understood from the following detailed description of typical preferred forms and applications of the invention, throughout which a master bushing and Kelly bushing construction drawings, in which:

Fig. 1 is a plan view of a rotary table showing one form of master bushing and Kelly bushing of the invention arranged in the operative positions and illustrating a typical Kelly in horizontal cross section. Fig. 2 is an enlarged horizontal detailed sectional view taken as indicated by line 2-2 on Fig. 3. Fig. 3 is an enlarged vertical detailed sectional view of the master bushing and Kelly bushing assembly taken substantially as indicated by line 3-3 on Fig. 1, showing the Kelly in side elevation. Fig. 4 is an enlarged, fragmentary vertical sectional view taken substantially as indicated by line 4-4 on Fig. 3. Fig. 5 is an enlarged fragmentary vertical detailed sectional view taken substantially as indicated by line 5-5 on Fig. 2. Fig. 6 is a fragmentary vertical detailed sectional view of the bushing construction showing a modified or alternative form of hold-down means. Fig. 7 is a fragmentary horizontal detailed sectional view of the construction shown in Fig. 6. Fig. 8 is a view similar to Fig. 3 illustrating another form of the invention embodying automatic hold-down latches showing the Kelly and the latch parts in side elevation. Fig. 9 is a horizontal detailed sectional view taken as indicated by line 9-9 on Fig. 8 and Fig. 10 is a fragmentary horizontal detailed sectional view taken as indicated by line 10-10 on Fig. 8.

The form of the invention illustrated in Figs. 1 to 5, inclusive, of the drawings, may be said to comprise, generally, a master bushing 10 to be arranged in a rotary table T, a Kelly bushing body 11, cage and roller assemblies 12 in the body 11, pilot means 13 on the body 11 for locating and centering the body as it is lowered into position, and means 14 for transmitting rotation or torque between the master bushing 10 and the Kelly bushing body 11.

The master bushing 10 is intended to be arranged in the rotary table T to receive pipe supporting slips and the Kelly bushing. The master bushing 10 is shaped to fit in the rotary table T and is preferably sectional to be readily assembled in the table. The table T has a central vertical opening with a polygonal upper portion 15 and a round or cylindrical major portion 16. The master bushing 10 is shaped to fit the table opening having a polygonal upper part 17 seated in the polygonal portion 15 and a cylindrical major lower portion 18 seated in the cylindrical opening portion 16. The upper side of the bushing 10 is preferably flat and is flush with the top of the table T when the bushing is in place. The master bushing 10 is provided with a central opening for receiving the slips for passing the Kelly K, drilling tools, etc., and for receiving parts of the Kelly bushing. The opening of the master bushing 10 has a conical or downwardly and inwardly tapered wall 20. The tapered wall 20 of the master bushing 10 preferably extends downwardly from the top of the bushing to a point adjacent the lower end of the bushing. The extreme lower portion of the master bushing opening may have a tapered wall 21 sloping upwardly and inwardly. A short cylindrical wall 22 occurs in the master bushing opening between the tapered walls 20 and 21 at the point of maximum restriction.

The master bushing 10 is preferably cored out to reduce its weight, having vertically extending spaces between its internal and external wall parts. It is preferred to make the master bushing 10 in two or more sections to facilitate its convenient assembly. In the construction illus-

trated the master bushing 10 is divided into two like or complementary sections S (see Fig. 2). The diametrical vertical plane of division of the master bushing 10 preferably has interfitting or interlocking ribs 23. The ribs 23 extend vertically of the inner sides of the bushing sections S and are engaged by relative vertical movement of the sections to effectively lock the sections against relative lateral movement. When the sections S are connected by means of the ribs 23 and seated in the opening of the table T, the master bushing 10 is, in effect, a continuous solid structure.

The Kelly bushing body 11 is provided to carry or contain the active Kelly engaging parts of the bushing. In accordance with the invention the body 11 is constructed for arrangement at the upper side of the master bushing 10 to rest on the master bushing. In the construction illustrated the bushing body 11 is an upright tubular member having an open upper end to receive the cage and roller assemblies 12. The upper end portion of the body 11 is cylindrical and threaded at 24, while the lower end of the body 11 is preferably flat and horizontal. A central downwardly projecting extension 25 is provided on the lower end of the body 11. The extension 25 may be an integral part of the body 11 and is adapted to extend into the opening of the bushing 10 with suitable clearance. The extension 25 is tubular having an opening 26 that continues upwardly to the interior of the tubular body 11. The upper portion of the opening 26 is enlarged in diameter providing a tapered upwardly facing annular shoulder 27. The body extension 25 serves to carry the pilot means 13.

In accordance with the broader aspects of the invention the Kelly bushing may have any selected or required form of Kelly engaging parts for transmitting rotation to the Kelly K. For example, the Kelly engaging parts of the Kelly bushing may be fixed relative to the Kelly bushing or may be anti-friction elements such as rollers. In the form of the invention herein described the Kelly bushing is provided with the cage and roller assemblies 12 for transmitting the rotation or torque to the Kelly K. In accordance with the usual practice the Kelly K is polygonal in transverse cross section and in the typical case illustrated the Kelly K has four vertical sides or faces F. The Kelly bushing embodies four cage and roller assemblies 12 arranged in the body 11. Each assembly 12 has a cage 28, vertically spaced pins 29 supported by the cage 28, and rollers 30 on the pins. The cages 28 have lower walls 31 resting on the internal lower surface 32 of the body 11 and the upper ends of the cages 28 may lie in or adjacent the plane occupied by the upper end of the body 11. The cages 28, while individual, have interlocking engagement in the body. The pins 29 extend transversely between the sides of the cages 28 and the sets or pairs of pins 29 lie in vertical planes parallel with the faces F of the Kelly K. The rollers 30 are rotatably supported on the pins 29 and are located so that they cooperate with the faces F of the Kelly K. The engagement of the rollers 30 with the Kelly K transmits rotation to the Kelly while allowing free vertical movement of the Kelly with respect to the bushing assembly. A cover ring 33 is removably threaded on the upper portion 24 of the body 11 and engages the upper ends of the cages 28 to hold the assemblies 12 in the body. The cover ring 33 is locked in place by a bolt 34 passed through openings in the ring

at a radial split in the ring. The upper ends of the cages 28 have threaded openings 35 and the reception of lifting rods for inserting and removing the assemblies 12. The cage and roller assemblies 12 may be of the general type disclosed and claimed in the Lynn, et al., Patent No. 1,914,-210, January 13, 1933.

The guide means or pilot means 13 is a locating or centering means arranged on the lower end of the Kelly bushing adapted to enter the master bushing 10 to bring the Kelly bushing into concentric relation to the master bushing when the Kelly bushing is lowered into place. The pilot means 13 comprises an elongate tubular sleeve 36 projecting downwardly at the lower end of the Kelly bushing body 11. The sleeve 36 is preferably cylindrical and fits the opening 26 of the body extension 25. The guide sleeve or pilot sleeve 36 extends downwardly beyond the extension 25 to project through the restricted cylindrical wall 22 into the flared lower part of the master bushing opening when the Kelly bushing is in place. The sleeve 36 is received by the cylindrical wall 22 with but slight clearance. An external enlargement 37 is provided at the upper end of the sleeve 36 to seat on the shoulder 27. The sleeve 36 arranged as just described, is removable vertically from the Kelly bushing when the cover ring 33 and the assemblies 12 are removed.

The pilot sleeve 36 is sectional to be readily assembled about the kelly K before being lowered into place. The sleeve 36 is preferably divided along a vertical plane into two like halves or sections. The plane of division or splitting of the sleeve 36 is indicated at 38. Means is provided for definitely locating the pilot sleeve 36 and for preventing relative rocking or spreading of the halves of the split sleeve. A key 39 is welded or otherwise fixed in a notch 40 in the lower wall of the body 11 and cooperates with notches 41 in the upper ends of the guide sleeve sections. Fig. 5 best illustrates the key construction. The notches 41 are preferably located at the plane of division 38 of the sleeve 36 so that the key 39 cooperates with both sections of the sleeve.

In accordance with the usual practice the kelly K has an upset portion or cylindrical portion 42 at its lower end presenting upwardly facing shoulders 43 at the lower ends of the faces F. The shoulders 43 are pitched downwardly and outwardly. The pilot means 13 has a part or parts engageable by the shoulders 43 to lift or raise the Kelly bushing from the master bushing 10 when the drilling string is pulled or raised and adapted to support the Kelly bushing on the kelly K when the kelly is arranged in the derrick and when the Kelly bushing is to be lowered into place in the master bushing.

An internal enlargement or projection is provided on the sleeve 36 to cooperate with the shoulders 43 of the kelly K. In the form of the invention being described this enlargement is removable and replaceable to adapt the Kelly bushing or at least the sleeve 36 for use with kellys of different sizes. An annular horizontal groove 44 is formed in the interior of the sleeve 36. The groove 44 preferably has dove-tailed or converging side walls and is spaced a substantial distance above the lower end of the sleeve 36. A split ring 45 is arranged in the groove 44. The sections of the split ring 45 may be slid into the groove 44 where the ends of the groove are open at the plane of division 38 of the sleeve 36. The ring 45 has dove-tailed or converging sides co-

operable with the walls of the groove 44 to be locked in place. The upper and lower sides of the ring 45 may slope or converge inwardly and the lower side of the ring has flat pitched faces angularly related to cooperate with the shoulders 43 of the kelly F. The relationship between the ring 45 and the lower end of the pilot sleeve 36 is such that the kelly portion 42 projects a substantial distance below the sleeve 36 to be readily engaged by tongs, or the like, when the shoulders 43 are in cooperation with the under side of the ring. This assures the easy connection and disconnection of the kelly when the Kelly bushing is on the kelly. The upset portion 42 of the kelly K is of substantial length and its lower end is formed for threaded connection with a sub 46 or other part of the drilling string.

The means 14 for transmitting rotation or torque from the master bushing 10 to the Kelly bushing comprises parts on the bushings engaged and disengaged by relative vertical movement of the bushings. In the preferred construction the means 14 comprises projecting parts on the Kelly bushing received in openings in the master bushing 10. As illustrated there are spaced downwardly projecting jaws, lugs, or drive parts 47 on the lower end of the Kelly bushing body 11 cooperable with openings 48 in the upper end of the master bushing 10. There may be four equally spaced torque transmitting parts 47 at or adjacent the margin or periphery of the bushing body 11, it being preferred to arrange the parts 47 a maximum distance from the central vertical axis of the bushing. The torque transmitting parts 47 may be integral with the body 11 and are preferably quite heavy. The inner and outer sides of the lugs or parts 47 may be curved concentrically with the vertical axis of the bushing. As best illustrated in Fig. 2 of the drawings the sides 48 of the parts 47 are flat and substantially radial relative to the central vertical axis of the bushing. This assures a full, even contact between the side surfaces of the parts 47 and the walls of the openings 48 providing an effective, durable torque transmission between the bushings. There may be raised finished surfaces 50 on the under side of the body 11 at or around the parts 47. The openings 48 communicate with the cored out interior of the master bushing 10 and the parts 47 may extend into the hollow master bushing. Openings 51 extend vertically through the parts 47 and the lower wall of the body 11 to communicate with the interior of the body. The openings 51 are provided to discharge or drain mud or other fluid from the interior of the body 11 and their lower ends empty into the interior of the cored out master bushing 10.

Means is provided to hold down the Kelly bushing, that is to prevent upward movement of the Kelly bushing relative to the master bushing. In the form of the invention being described this means is associated with the torque transmitting means 14. The trailing sides 52 of the parts 47 relative to the normal direction of rotation of the rotary table and the trailing walls 53 of the openings 48 have a rake or are undercut to have latching or locking cooperation. The surfaces 52 and the walls 53 slope upwardly and forwardly relative to the normal direction of rotation of the rotary table and when engaged serve to definitely hold the Kelly bushing against upward movement relative to the master bushing. The parts are proportioned so that the leading sides of the lugs or parts 47 have suitable clearance with the lead-

ing walls of the openings 48. This clearance allows the parts 47 to be readily entered into the openings 48. The pitched or undercut surfaces 52 and walls 53 are correspondingly sloped and are formed to evenly bear throughout their 5 extents.

In operation the Kelly bushing is first assembled on the kelly K. The Kelly bushing body 11 with the cage and roller assemblies 12 removed is arranged on the master bushing 10 and may be 10 positioned to have its drive parts 47 in the openings 48. The kelly K is hoisted or swung over the bushings and is lowered down through the body 11 and the master bushing 10. With the kelly K extending through the bushings the guide sleeve 15 or pilot sleeve 36 is assembled around the kelly and lowered into place so that its enlarged portion 37 bears on the shoulder 27. In performing this operation lifting handles or rods may be 20 threaded into tapped openings 54 in the portion 37 to facilitate the handling of the split sleeve 36. The cover ring 33 is then threaded from the body 11 and raised and the cage and roller assemblies 12 are lowered into the body 11. The assemblies 12 may be lowered into place on lifting rods or 25 handles threaded into the openings 35. The cover ring 33 is then lowered onto the body 11 and threaded on the portion 24 to engage against the upper ends of the assemblies 12. This completes the assembling of the Kelly bushing on the kelly K, and so long as the Kelly bushing is in service it may remain on the kelly. The ring 45 is engageable by the shoulders 43 so that the Kelly bushing may be hoisted or raised and lowered by means of the kelly K.

When the drilling string is made up and it is desired to employ the kelly K and the Kelly bushing to drive the drilling string, the kelly K connected with the upper end of the string is lowered. The Kelly bushing is supported on the kelly K by the engagement of the ring 45 with the shoulders 43 and the Kelly bushing moves downwardly with the kelly. The Kelly bushing is lowered until the guide sleeve or pilot sleeve 36 enters the master bushing 10. The engagement of the lower end of the guide sleeve 36 with the sloping wall 20 locates or centralizes the Kelly bushing body 11 and when the guide sleeve 36 enters and passes through the cylindrical wall 22 the bushing body 11 is co-axial with the master bushing 10. This automatically brings the parts 47 into concentric relation with the openings 48. The lower ends of the parts 47 may rest on the upper surface of the master bushing 10 to temporarily support the Kelly bushing. The rotary table T is then rotated or turned slightly in the righthand direction. As there is no engaged drive between the master bushing 10 and the body 11, the master bushing turns with respect to the Kelly bushing and the openings 48 are brought under the parts 47 and the parts 47 automatically fall into the openings 48. In this connection it is to be observed that the pilot sleeve 36 is engaged in the central cylindrical wall 22 of the master bushing 10 to hold the body 11 centralized so that the parts 47 are circumferentially aligned with the openings 48. With the parts 47 engaged in the openings 48 the apparatus is in condition for operation.

When the table T is rotated in a righthand direction the surfaces 52 and the walls 53 cooperate and their engagement definitely holds or locks the body 11 and the parts associated therewith against upward movement relative to the master bushing 10. In the drilling operation the

torque or rotation is transmitted from the master bushing 10 to the Kelly bushing through the parts 47 engaged in the openings 48 and the rollers 30 of the Kelly bushing contact the flat faces F of the kelly K to transmit rotation to the kelly and the drilling string. The kelly K is, of course, movable vertically relative to the bushing assembly. When the drilling string is to be pulled the kelly K is raised, bringing the shoulders 43 against the ring 45 and the Kelly bushing is hoisted or raised with the kelly K. The clearance in the openings 48 allows the parts 47 to move upwardly out of the openings when the Kelly bushing is positively lifted by the kelly K. The improved Kelly bushing is easily and quickly connected with the master bushing 10 for the transmission of rotation without the use of sledges or crowbars and requires no manually operated or controlled hold-down devices or latches for preventing upward movement of the Kelly bushing relative to the master bushing 10 when the equipment is in operation.

Figs. 6 and 7 of the drawings illustrate an alternative or modified form of hold-down means. The construction may be the same as described above, except that the torque transmitting means 14 is modified to embody spring hold-down means. The torque transmitting parts 47^a have flat vertical sides 52^a and the side walls of the openings 48^a are flat and vertical. In the preferred arrangement the sides of the parts 47^a and the side walls of the openings 48^a are radial with respect to the vertical axis of the bushing assembly and cooperate with but little clearance. Notches 55 are formed in the top of the master bushing 10^a to join the openings 48^a. Blocks 56 are welded or otherwise secured in the notches 55 and their lower ends overhang to form shoulders 57. The blocks 56 may be hard faced to be long-wearing. The outer faces of the torque transmitting parts 47^a have vertically extending grooves 58. Raised faces 59 may be provided above the grooves 58 and leaf springs 60 are seated on the faces 59. Screws 61 may secure the springs 60 to the body 11^a. The springs 60 extend downwardly at the mouths or outer sides of the grooves 58 and are shaped to have holding or latching cooperation with the overhanging lower corners 57 of the blocks 56. The springs 60 have outwardly projecting portions 62 for cooperating with the block corners 57 and the lower end parts of the springs 60 slope downwardly and inwardly to readily slide down the faces of the blocks 56. The upper and lower corners of the blocks 56 may be rounded or bevelled off.

When the Kelly bushing is lowered with the parts 47^a aligned with the openings 48^a, the sloping lower ends of the springs 60 cooperate with the blocks 56 and cause inward retraction of the springs. When the parts 47^a move downwardly in the openings 48^a the spring parts 62 snap under the corners 57 of the blocks 56 to latch or hold the Kelly bushing against upward movement relative to the master bushing. The Kelly bushing provided with the hold down means illustrated in Figs. 6 and 7 of the drawings may be employed and operated in the same manner as the previously described form of the invention.

The embodiment of the invention illustrated in Figs. 8, 9 and 10 of the drawings may be said to comprise, generally a master bushing 10^b, a Kelly bushing body 11^b, cage and roller assemblies 12^b in the body 11^b, means 14^b for transmitting rotation between the master bushing and the Kelly

bushing, guide means or pilot means 13^b for centering the body 11^b when the same is lowered into place, and means X associated with the pilot means 13^b for holding the Kelly bushing down in its operative position.

The master bushing 10^b, the Kelly bushing body 11^b and the cage and roller assemblies 12^b are the same as in the previously described form of the invention and corresponding reference numerals are applied to their corresponding parts. In this construction the extension 25 on the lower end of the body 11^b is eliminated, the lower wall of the body 11^b having an opening 64 considerably larger in diameter than the kelly K.

The means 14^b for transmitting rotation or torque from the master bushing 10^b to the Kelly bushing 11^b comprises lugs or parts 47^b projecting from the lower end of the body 11^b and openings 48^b in the top of the master bushing 10^b receiving the parts 47^b. There is a plurality of spaced parts 47^b and a corresponding number of openings 48^b for receiving the parts. In this form of the invention the opposite sides of the parts 47^b and the side walls of the openings 48^b are preferably flat and vertical and radial with respect to the central vertical axis of the bushing assembly. The torque transmitting parts 47^b are received in the openings 48^b with suitable slight clearance. The parts 47^b have vertical drain openings 51^b for discharging mud or the like from the interior of the body 11^b into the open bottomed master bushing 10^b.

The guide means or pilot means 13^b operates to locate or centralize the kelly bushing when the same is lowered into place to bring the parts 47^b into concentric relation with the openings 48^b. The pilot means 13^b includes a rigid guide sleeve or pilot extension 36^b on the lower end of the body 11^b. The opening 66 in the sleeve 36^b receives or passes the kelly K with substantial clearance. The sleeve 36^b extends upwardly in the opening 64 and has a head or flange 67 on its upper end seating on a shoulder 68 formed on the wall of the opening 64. The sleeve 36^b projects a substantial distance from the body 11^b and is sufficiently long to project into the lower flared part of the master bushing opening when the Kelly bushing is in position. The lower end of the sleeve 36^b is cooperable with the sloping wall 20 and the cylindrical wall 22 to locate and centralize the Kelly bushing 11^b.

The hold down means X automatically latches the Kelly bushing against upward movement when it is lowered into the master bushing 10^b on the kelly K and is automatically released when the kelly K is raised to lift the Kelly bushing from the rotary table. The means X includes windows or openings 69 in the master bushing 10^b. The openings 69 occur in the upper portion of the wall 20 and may be diametrically opposite. The upper walls of the openings 69 slope downwardly and outwardly while the lower walls of the openings 69 slope downwardly and inwardly. Pivoted keepers or latches 70 are mounted on the pilot extension or sleeve 36^b to cooperate with the openings 69. Sets or pairs of ears 71 are provided on the guide sleeve 36^b and vertical slots 72 extend into the sleeve 36^b from its upper end and separate or space the ears 71. Pins 73 pivotally support the latches 70 between the ears 71 to extend outwardly from the sleeve 36^b and to project inwardly in the slots 72. The outer ends of the latches 70 are curved or sloped to engage upwardly and outwardly against the upper walls of the openings 69 and this engagement 75

holds or locks the Kelly bushing against upward movement relative to the master bushing. The lower sides of the latches 70 are adapted to engage against the lower walls of the openings 69 to limit the downward and outward pivoting of the latches.

Novel means is provided for controlling the latches 70. A split sleeve 74 surrounds the kelly K within the guide sleeve 36^b. The opening of the split sleeve 74 is polygonal and proportioned to freely pass the kelly K. The halves of the split sleeve 74 are held in the correct relation by dowels 75 arranged through openings at the plane of division of the sleeve, see Fig. 9. Diametrically opposite sides of the sleeve 74 have flat vertical inset faces 76 providing adequate clearance for the reception of the inner portions of the latches 70. The lower end of the split sleeve 74 may rest on a shoulder 77 formed on the interior of the guide extension or sleeve 36^b. The upper end of the split sleeve 74 may be spaced below the interior of the body 11^b. Fingers 78 project outwardly at the upper ends of the flat faces 76 and extend through the slots 72. The lower sides 20 of the fingers 78 are engageable with the upper sides of the latches 70. A coiled spring 79 is arranged under compression between the fingers 78 and the lower ends of the cage and roller assemblies 12^b. The spring 79 is within the guide sleeve 36^b and surrounds the kelly K with substantial clearance. The spring 79 normally urges or holds the split sleeve 74 down so that the fingers 78 retain the latches 70 in cooperation with the openings 69.

Means is provided for automatically releasing the latches 70 from the openings 69 when the kelly K is raised to lift the Kelly bushing from the master bushing 10^b. Downwardly and outwardly sloping cam faces 80 are provided on the exterior of the sleeve 74 at the lower ends of the flat faces 76 and the lower ends of the latches 70 are shaped to cooperate with the cam faces. The lower end of the split sleeve 74 is adapted to be engaged by the shoulders 43 of Kelly K and may have sloping shoulders 82 for engagement by the shoulders 43. When the Kelly is raised from a position such as shown in Fig. 8 its shoulders 43 come into engagement with the shoulders 82 and the sleeve 74 is raised against the action of the spring 79 so that the cam faces 80 retract or pivot the latches 70 out of the openings 69. Following retraction of the latches 70 continued upward movement of the Kelly K is transmitted to the body 11^b so that the Kelly bushing may be raised with the Kelly.

When the Kelly bushing illustrated in Figs. 8, 9 and 10 of the drawings is to be used the body 11^b carrying the cover ring 33 but without the assemblies 12^b is seated on the master bushing 10^b, the Kelly K is suspended over the bushing assembly and the spring 79 is run up over the lower end of the Kelly and held in an elevated position. The Kelly K is then lowered down through the bushing assembly to bring the upset portion 42 below the shoulder 77. The split sleeve 74 is then assembled around the Kelly K, the dowels 75 being arranged in place and the sleeve 74 is lowered into position to rest on the shoulder 77. Lifting handles or rods may be employed in lowering the sleeve 74 into position. The spring 79 is then run down the Kelly K to rest on the fingers 78. The cover ring 33 is disconnected from the body 11^b and raised and the cage and roller assemblies 12^b are placed in the body 11^b. The cover ring 33 is then reapplied to

the body 11^b to hold down the assemblies 12^b. The Kelly K is then raised to bring its shoulders 43 against the shoulders 82 and the upward movement of the Kelly is continued to lift the Kelly bushing out of the master bushing 10^b. The latches 10 are then positioned and secured in place by the pins 13. The Kelly K is then lowered to return the Kelly bushing to its operative position. In this operation the pilot sleeve 36^b engages in the tapered wall 20 and the cylindrical wall 22 to locate or centralize the Kelly bushing so that the parts 47^b are conditioned to enter the openings 48^b. The rotary table is started and as the master bushing 10^b rotates with respect to the Kelly bushing 15 the openings 48^b are brought to positions to receive the parts 47^b. The parts 47^b automatically fall into the openings 48^b, the sleeve 36^b serving to hold the Kelly bushing centralized with respect to the master bushing.

When the kelly K is lowered the shoulders 43 move away from the shoulders 82 and the sleeve 74 is allowed to move downwardly. This downward movement of the sleeve 74 is accompanied by outward pivoting of the latches 80 and the noses of the latches are brought into cooperation with the openings 69. Thus the latches 70 automatically latch the Kelly bushing against upward movement in the master bushing 10^b. The Kelly bushing may remain assembled about the kelly K throughout the drilling operations. The shoulders 43 of the kelly K are cooperable with the shoulders 82 to lift the Kelly bushing from the master bushing and when the Kelly bushing is to be returned to its operative position the kelly K is merely lowered as above described, and the sleeve 36^b cooperates with the walls 20 and 22 to centralize the Kelly bushing so that the parts 47^b are oriented for immediate engagement in the openings 48^b when rotation of the rotary table 40 is initiated.

Having described only typical preferred forms and applications of my invention, I do not wish to be limited or restricted to the specific details herein set forth, but wish to reserve to myself any variations or modifications that may appear to those skilled in the art or fall within the scope of the following claims:

Having described my invention, I claim:

1. In combination, a master bushing having a central opening, the opening having a tapered slip receiving portion and a lower generally cylindrical portion, a drive bushing for transmitting rotation to a drive stem and adapted to rest on the upper end of the master bushing, parts on the upper end of the master bushing and the lower end of the drive bushing spaced outwardly from the central opening engageable by relative vertical movement when the drive bushing is made to rest on the upper end of the master bushing and operable when engaged to transmit rotation between the bushings, and a pilot element projecting from the lower end of the drive bushing of sufficient length to extend through said tapered portion of the opening and slidably and turnably engage in said generally cylindrical portion of the opening to bring said parts into position for ready engagement when the drive bushing is lowered and turned relative to the master bushing.

2. In a rotary table structure including a master bushing for arrangement in the table and having a central opening, an opening in the table structure offset from the central opening, a drive bushing to be removably carried by the master

bushing, a part projecting from the lower end of the drive bushing adapted to enter the offset opening for the transmission of rotation and to allow the lower end of the drive bushing to rest on the upper end of the table structure, the lower end of said part being engageable with the upper end of the table structure when said part is out of alignment with the offset opening, and a pilot element extending from the lower end of the drive bushing to enter said central opening and centralize the drive bushing so that said part is readily entered in said offset opening and turnable in said central opening so that relative turning between the drive bushing and table structure will cause said part to enter the offset opening.

3. A Kelly bushing for use with a rotary table assembly having a central opening and openings spaced about and spaced from the central opening comprising a bushing body, spaced parts projecting from the lower end of the body adapted to be entered in the second named openings for the transmission of rotation from the table assembly to the body, and a pilot element on the lower end of the body projecting downwardly beyond said parts adapted to turnably engage in the central opening to centralize the body relative to the table assembly so that said parts may be readily entered in said second named openings 30 by relative turning between the bushing and table assembly.

4. A Kelly bushing for use with a rotary table assembly having a central opening and an offset opening comprising a body to be arranged on the 35 table assembly, a projecting part at the lower end of the body adapted to enter the offset opening for the transmission of rotation between the table assembly and bushing, a guide extension on the lower end of the body projecting downwardly beyond said part adapted to cooperate with the central opening to position the part for easy insertion in said offset opening, and means associated with the guide extension for holding the body against upward movement.

5. A Kelly bushing for driving a Kelly having a shoulder adjacent its lower end and adapted for use with a master bushing having a central opening and an offset opening, the Kelly bushing comprising a body to engage around the Kelly, a part projecting from the body to engage in the offset opening for the transmission of rotation from the master bushing to the body, a centering extension on the lower end of the body for slidably and turnably engaging in the central opening when the body is lowered into place so that said part may be readily entered in said offset opening by relative turning of the bushings during or following said lowering of the body, and an internal projection in the extension engageable by the shoulder on the Kelly so that the body may be elevated and lowered by the Kelly.

6. A Kelly bushing for driving a Kelly and adapted for use with a rotary table assembly having a central opening and an offset opening, the Kelly bushing comprising a body to engage around the Kelly and adapted to rest on the upper end of the table assembly, a part projecting from the lower end of the body to engage in the offset opening for the transmission of rotation from the table assembly to the body when the body is resting on the upper end of the table assembly, means carried by the body for transmitting rotation to the Kelly, and a split sleeve assembled around the Kelly and carried by the body to project from its lower end, the sleeve being turn-

ably engageable in the central opening so that said part may be readily entered in said offset opening by relative turning between the body and table assembly.

7. A Kelly bushing for driving a Kelly and adapted for use with a rotary table assembly having a central opening and an offset opening, the Kelly bushing comprising a body to engage around the Kelly and adapted to rest on the upper end of the table assembly, a part projecting from the lower end of the body to engage in the offset opening for the transmission of rotation from the table assembly to the body, the offset opening and part having contacting surfaces pitched with respect to the vertical for holding the body against upward movement relative to the master bushing, means carried by the body for transmitting rotation to the Kelly, and a split sleeve assembled around the Kelly and carried by the body to project from its lower end and slidably and turnably engageable in the central opening to centralize the body relative to the table assembly so that relative turning between the table assembly and body will engage said part in the offset opening.

8. A Kelly bushing for driving a Kelly and adapted for use with a master bushing having a central opening and an offset opening spaced from the central opening, the Kelly bushing comprising a body to engage around the Kelly, a part projecting from the body to engage in the offset opening for the transmission of rotation from the master bushing to the body, a centering extension on the lower end of the body engageable in the central opening to centralize the body when it is lowered into place so that said part may be readily entered in said offset opening, and spring means at said offset opening and said part for releasably holding the body against upward movement relative to the master bushing.

9. A Kelly bushing for driving a Kelly and adapted for use with a master bushing having a central opening and an offset opening spaced from the central opening, the Kelly bushing comprising a body to engage around the Kelly, a part projecting from the lower end of the body to engage in the offset opening for the transmission of rotation from the master bushing to the body, a centering extension on the lower end of the body turnably and slidably engageable in the central opening to centralize the body when it is lowered into place so that said part may be readily entered in said offset opening, and spring means at said offset opening and said part for releasably holding the body against upward movement relative to the master bushing, the spring means including a shoulder at said offset opening and a spring on said part for engaging under the shoulder.

10. A bushing structure for use in a rotary table to drive a Kelly comprising a master bushing to be carried by the table having a central opening and a shoulder on the wall of the opening, a drive bushing body to be arranged on the master bushing, a downward extension on the body for entering the opening of the master bushing, a latch on the extension engageable with said shoulder when the extension enters the opening to hold the body against upward movement, and a control for releasing the latch from said shoulder when the Kelly is raised beyond a given point.

11. A bushing structure for use in a rotary table to drive a Kelly comprising a master bushing to

be carried by the table having a central opening and a shoulder on the wall of the opening, a drive bushing body to be arranged on the master bushing, a downward extension on the body for entering the opening of the master bushing, a latch on the extension engageable with said shoulder when the extension enters the opening to hold the body against upward movement, a socket in the top of the master bushing, a drive lug on the lower end of the body for engaging in the socket, the extension serving to centralize the body so that the lug is oriented for ready engagement in the socket, and a control for releasing the latch from said shoulder when the Kelly is raised beyond a given point.

12. A bushing structure for use in a rotary table to drive a Kelly comprising a master bushing to be carried by the table having a central opening and a shoulder on the wall of the opening, a drive bushing body to be arranged on the master bushing, a downward extension on the body for entering the opening of the master bushing, a latch on the extension engageable with said shoulder when the extension enters the opening to hold the body against upward movement, and a control for releasing the latch from said shoulder when the Kelly is raised beyond a given point, the control including a shiftable spring-urged sleeve in the extension, a cam on the sleeve for retracting the latch, and a face on the sleeve engageable by the Kelly to move the sleeve.

13. A Kelly bushing for use with a master bushing having a central opening comprising a body for arrangement on the master bushing, a part on the body engageable with the master bushing for the transmission of rotation, an extension on the body engageable in the opening to centralize the body, and latch means on the extension cooperable with the master bushing to hold the body against upward movement.

14. A drive bushing for use on a master bushing having a central opening to drive a drill stem having an upwardly facing shoulder, the drive bushing comprising a body to be arranged on the master bushing to rotate therewith, means on the body for transmitting rotation to the drill stem, a split sleeve assembled around the drill stem and connected with the body to extend from the lower side of the body, the sleeve being engageable in the opening to centralize the body, and a removable insert in the sleeve engageable by said shoulder whereby the body may be raised and lowered by the drill stem.

15. A rotary assembly having driving sockets therein comprising a table having a central bushing receiving opening, a table bushing in said central opening and also having a central opening, the central opening of the bushing having an upper inwardly and downwardly tapered portion and a lower cylindrical portion, a drive bushing for transmitting rotation from said table assembly to a drive stem, said drive bushing having depending drive pins on an upper portion, a pilot element projecting from the lower end of the drive bushing of sufficient length to extend through said tapered portion of the central opening of the table bushing and slidably and turnably engage in said cylindrical portion to properly center the drive bushing in the table bushing and bring said pins into position to engage the sockets in the rotary assembly.

SPENCER W. LONG,

DISCLAIMER

2,306,130.—*Spencer W. Long, Inglewood, Calif. WELL DRILLING APPARATUS.*
Patent dated Dec. 22, 1942. Disclaimer filed Oct. 10, 1947, by the assignee,
Baash-Ross Tool Company.

Hereby enters this disclaimer to claims 2, 3, and 6, of said patent.
